UNITED STATES PATENT OFFICE

ERNST FOERSTER, OF GLOGAU, GERMANY

TIME RECORDING DEVICE

Application filed December 28, 1929, Serial No. 417,155, and in Germany September 19, 1928.

The invention relates to a time controlling device for cash registering apparatus, connected with the cash registering apparatus in such a manner, that a print of the 5 time indication on the cash controlling strips is effected independently of the other mechanism by a clockwork of the time printing device within definite periods, while independently of the other driving mechanism of 10 the cash registering apparatus a clockwork of any suitable type will actuate type bars, which will mark the time on the control strip of the cash registering apparatus.

It has already become known to arrange in 15 cash registering apparatus time printing mechanism, but these arrangements possess the drawback of deficient survey and a restriction of their function, which did not admit the variety of use as with the subject 20 matter of application.

The present invention shows the advantage of the functioning of the time printing device independently of the cash register mechanism in contradistinction to the known 25 time printing devices, which are dependent on the cash registering mechanism. By means of the novel arrangement a considerable increase of the supervision through the cash registering apparatus, an increase of 30 economical advantages, the indication of the time within the realm of the supervision of cash transactions, the education to a rational use of the salesmen, the simultaneous use as 35 controlling block for the employees, the furtherance of test and trial purchases and supervision over fraudulent manipulations with the till outside business hours is obtained.

40 The essential characteristic feature of the invention is to be seen in the method of connecting a control printing clock with a cash registering apparatus in order to obtain the print of the time indication on the controlling strip of the cash register for the purpose of recording the item within definite 45 periods.

Some modes of execution of the arrangement according to the invention are illustrated 50 in the drawings by way of example, with-

out restricting the invention to the examples shown.

Figure 1 is a perspective view of a suitable device.

Figure 2 is a side elevation partly in section on line A—B of Figure 1,

Figure 3 is a vertical section through the system of guiding levers,

Figure 4 shows the diagram of an arrangement of time marks on an enlarged scale,

Figures 5 and 6 show a modification, namely,

Figure 5 a perspective view with the front-plate removed, and

Figure 6 a longitudinal section on line C—D of the Figure 5,

Figure 7 illustrates another modification, being a perspective view,

Figure 8 is a transverse section on line E—F of Figure 7, and

Figure 9 shows by way of example the construction and action of the pressure bolt 32 of Figures 7 and 8.

The abutment rails 2 are axially arranged in the container 1 and they are securely 75 guided by grooves 3. Guiding forks 4 are secured in the centre of the abutment rails 2, into which engage corresponding guiding rollers 5 each provided at the head of a segment 6 (Figure 2). The segments 6, of which 80 one is arranged beneath each abutment rail, are pivotally mounted at 7 and they are subject to the action of the tension springs 8 and return springs 9 and they terminate in toothed segments 10. Each toothed segment 85 10 is engaged by a driving disc 11, connected with a clockwork and being rotated clockwise. The various arcs of the driving disc 11 are provided each time with teeth only over one eighth of their periphery, so that always 90 one abutment rail after the other is advanced, while all rails will touch at the point 12 (Figures 1 and 2). This aim of touch is the controlling strip 13 of a cash registering apparatus in front of which strip the customary 95 inked ribbon 14 is provided.

The operation is as follows:

The driving disc 11 (Figure 2) engages the toothed segment 10 and moves the latter together with the abutment rail 2 against the 100

action of the spring 8 backwards for such a time, until the roller 5 has reached the point 15. At this moment the teeth of the driving disc disengage those of the segment 10, the spring 8 snaps back and advances the roller 5 to the point 16 and the head of the abutment rail 2 will beat at 12 against the inked ribbon 14 and the controlling strip.

As the head of the said rail is provided with a type of the time mark, the latter will be printed on the controlling strip. The return spring 9 acts upon the nose 17 and returns the segment 6 to its inoperative position. An accurate adjustment is obtained by means of the stop 18, the abutment rail will thus at once release the controlling strip again. No figures are used as time indicating signs, but the diagram represented in Figure 4. As the clock continues moving, while the controlling ribbon is often at rest, the marks would be printed one on top of the other and they would become indistinct. By using the present diagram the picture 19 (Figure 4) will be formed.

In the modification illustrated in Figures 5 and 6 the body of the clock 20 carries a bolt supporting disc 21, which is turned clockwise by means of a clockwork. On the said disc 21 the pressure bolts 22 are arranged axially and displaceable; they are subjected to the action of the tension springs 23. The printing or stamping bolts 22 are provided with stop pins 24, which will engage the front edge 25 of the disc 21, and while they penetrate through said disc they terminate in guiding rollers 26. The segment 27 attached to the body of the clock is situated in the path of the rollers 26.

The operation is as follows:

As soon as the guiding rollers 26 are in engagement with the segment 27 (Figure 5) they are forced back together with the printing bolts according to the curve of the segment until the termination of the curve is reached at 28. The tension springs 23 will then snap the bolt against the inked ribbon and the controlling strip thus causing the touch and print of the sign or mark. The double springs 29 effect an instantaneous release of the controlling strip. With this modification too the use of the diagram of time marks according to Figure 4 is recommendable.

A third modification of the invention is illustrated in Figures 7 and 8.

The body 20 of the clock is provided with the disc 30 turned clockwise by a clockwork and carrying the segments 31. Above that disc 30 the printing bolt 32 carrying the time marks is displaceably mounted in known manner in such a way, that a roller 33 attached thereto lies in the path of the segment 31.

The operation of the device is as follows: The segments 31 will force back the print-

ing bolt 32 against the action of the tension springs 34 by means of the roller 33 for such a time (Figure 7) until a recess 35 of the segment passes. Then the bolt 32 will snap back causing a print and touch on 13 and 14 and it is returned into its initial position by means of the double springs 36. If the diagram of time marks according to Figure 4 is used, eight discs 30 are required according to the number of marks.

But the printing bolts may be so constructed that it is provided at its touching or engaging end with a disc carrying the eight time marks, which disc is turned through the segments 31 according to the time and is caused to print at 13 and 14.

In the modifications shown in Figures 1 and 5 there will be used only eight hour marks corresponding to the eight hours business day and also for the purpose of rendering the entire driving mechanism proper simpler.

Figure 7 shows the construction of a printing bolt, which will be actuated by the four segments 31 each quarter of an hour, if the disc 30 is turned each hour. All modifications shown in Figures 1, 5 and 7 can be provided without any difficulty with any subdivision governed by requirements and by designing them as time printing devices, and they only show possible constructions by way of example.

In the constructional example shown in the drawings only four segments are shown in Figure 7 and a device for only eight time-indicating marks in Figure 9 for the sake of clarity.

In practice a stamping mechanism is desirable which prints five minute marks at the end of every five minutes and at the same time stamps the corresponding hour indicating marks at the end of each hour. For this purpose an arrangement as shown in Figure 7, for example, is provided with a printing bolt having twelve time-indicating marks, the said bolt being actuated by means of a clock-work mechanism every five minutes. Besides these time indications the hours would be indicated by a similar arrangement, in which the appropriate hour-indicating mark is released and printed at the end of each hour. The result is apparent from the drawing of the record strip.

For instance on the printing bolt 32 is provided at its printing end a gear wheel 37 provided in this instance with eight teeth, corresponding to the desired division of time, and the said gear wheel is retained in its position of rest by means of pawls 38 and locking spring 39. On the axis of the gear wheel in the rear of the printing bolt 32 is mounted rigidly the marking disc 40 provided with printing types. On one side of the bearing for the printing bolt a pushing angle lever 41 having a tension spring 43 is arranged in such a manner that on tensioning the whole print-

ing bolt 32, it is pushed into a tooth-gap of the gear wheel 37, while a catch 42 on the printing bolt 32 will maintain the angle 41 in the proper position.

5 At the tensioning 34 of the printing bolt 32 the gear wheel 37 is advanced towards the angle 41. This latter will push and turn the gear wheel 37 together with the disc 40 carrying the printing types, until under the action of the locking spring 39 the pawl 38 will snap into the next tooth-gap while at the same time also the termination of the tensioning of the printing bolt is reached. When the printing bolt is flung back into its position of rest the pushing angle too will be returned to its former position of rest by means of its tensioning spring 43 and it is ready in front of the next tooth-gap.

I claim:

20 1. A printing device adapted to imprint on a record sheet, comprising a plurality of slidably guided abutment bars, each bearing a distinct time mark, a clock mechanism, a plurality of pivotally mounted members having pivotal engagement with the abutment bars and interrupted engagement with the clock mechanism for actuating an appropriate abutment bar to impinge upon the strip at predetermined intervals, and means for causing the rebound of the abutment bars immediately after impingement upon the strip.

25 2. A printing device adapted to print a time indication on a record sheet, comprising a plurality of abutment bars, each bearing a distinct time mark, a clock mechanism, discs associated with the clock mechanism, said discs having teeth on parts of their peripheries, toothed segments engaged with the teeth of the discs and pivotally connected

30 with the abutment bars for sliding the same in longitudinal directions.
